UNITED STATES PATENT OFFICE.

OLIVER J. MOUSSETTE, OF RICHMOND HILL, NEW YORK.

MEASURING PUMP.

Application filed July 13, 1925. Serial No. 43,357.

This invention relates to apparatus whereby a measured quantity of a liquid commodity may be supplied retail purchasers and the object of the invention is to provide a simple and inexpensive mechanism which will be efficient in operation, not apt to get out of order and easily applied to or removed from a given container. The invention provides a device which is compact and will, therefore, occupy little space in or upon the container and which includes the means whereby solid constituents of the commodity may be distributed equally throughout the volume thereof. The invention is illustrated in the accompanying drawings and consists in certain novel features which will be hereinafter first fully described and then more particularly pointed out in the appended claims.

In the drawings:

Figure 1 is a sectional elevation of a measuring pump embodying my improvements;

Fig. 2 is a top plan view of the pump;

Fig. 3 is a front elevation with a part of the operating lever or handle broken away and in section;

Fig. 4 is a detail horizontal section on the line 4—4 of Fig. 1, and

Fig. 5 is a bottom plan view of the lower end of the pump pipe.

The pump of my present invention may be applied to a barrel or other container for liquids which is indicated at 1 and may be of any well-known or approved construction. The pump is supported by the top of the container and includes a head or cap 2 comprising essentially a rim adapted to fit closely within an opening provided therefor in the top of the container and a top plate 3 forming a closure and having its edge 4 slightly overlapping the rim whereby to rest upon the top of the container, as clearly shown in Fig. 1. The top of this head is provided centrally with a hub or depressed portion 5 having an internally threaded bore to receive the upper end of a pipe or pump tube 6 which depends within the container 1 and has an annular enlargement or rib 7 at its lower end which is externally threaded. A second pump tube 8 has its upper end fitted within the lower end of the pipe or tube 6 to form a frictional slip joint therewith so that the two pipes may be telescopically adjusted to conform to the height of the container in which they are

placed. A gland 9 containing a gasket 10 is threaded onto the annular enlargement 7 so as to bind the pipes 6 and 8 together in a set relation. The lower end of the pipe 8 is equipped with an inlet or suction head 11 which may be threaded directly onto the lower end of the pipe 8 but is preferably connected thereto by an intermediate coupling 12 threaded onto the pipe and into the inlet head, as clearly shown in Fig. 1. The lower end or edge of the inlet head 11 is provided with spaced lugs 13 whereby it may rest upon the bottom of the container 1 and will provide spaces at the said bottom through which the liquid may flow into the head. At an intermediate point in the height of the head is a cross bar or spider 14 which forms a guide for the stem 15 of a check valve 16, the valve seating upon an annular valve seat 17 provided therefor within the head above the spider or cross bar 14. A stop washer 18 is carried by the lower end of the valve stem 15 and serves to limit the opening movement of the valve by its contact with the spider or cross bar 14, as will be readily understood. It will be seen that normally the weight of the valve will hold it seated so that inflow of the liquid into the head 11 will be prevented but if suction be created above the valve the pressure of the liquid will raise the valve so that the liquid may then flow upwardly through the head past the valve to be discharged.

Disposed above the closure 2 is a measuring vessel or bowl 19 which is provided at one side with a discharge spout 20 through which the measured quantity of the liquid commodity will flow for delivery into a receptacle held or disposed adjacent the end of the spout. The extremity of the spout 20 is normally closed by a gate 21 pivotally mounted on the upper side of the spout in position to extend across the end of the same and normally held in its lowered closed position by a weighted arm 22 projecting outwardly from its upper edge. The bowl 19 is constructed with a channel 23 extending downwardly and then outwardly from its bottom and rising at its outer end into the spout 20, providing a seat 24 for a check valve 25 in the form of a disk adapted to rest normally upon the seat 24 and having a stem 26 rising within a guide box 27 secured in the upper side of the spout immediately adjacent the bowl

and housing a pressure spring 28 to augment the weight of the valve in holding it normally seated. The bottom of the bowl 19 is further constructed with a depending hub or tubular member 29 which is threaded into the depression 5 of the closure 2 whereby to secure the bowl firmly in place upon the closure and yet permit its removal when necessary. Within this hub member 29 is a guide bar or spider 30 and in the bottom of the bowl immediately over said spider or guide bar is a central valve seat 31. A disk valve 32 seats normally upon the seat 31 and has a depending stem 33 which passes through and is guided by the bar or spider 30, a stop washer 34 being secured to the lower end of the stem to limit the opening movement of the valve by contact with the spider or bar in an obvious manner.

The upper end portion of the bowl 19 is expanded annularly and presents a curved portion 35 which forms a seat for a flexible diaphragm 36 of rubber, leather, thin pliable metal or other material which may be found most desirable in any particular instance. This diaphragm has its upper end portion extended laterally outward to rest upon the flange 37 at the upper edge of the bowl and be secured upon said flange by the edge of a cover 38 which is bolted to the flange 37, as will be understood. The cover 38 is provided centrally with a guide sleeve 39 rising therefrom, and slidably fitted within this guide sleeve is a plunger rod 40, the upper end of which is formed into a fork 41 receiving and pivotally secured to the lever handle 42. The front end of the lever or handle 42 is free, as shown in Fig. 1, while its rear end is pivoted to a link or rocking standard 43 pivoted to and rising from a post 44 on the cover 38, as clearly shown. The lower end of the plunger rod 40 is reduced in diameter to provide a shoulder 45, the reduced portion extending centrally through the diaphragm 36 and being threaded to receive a nut 46 bearing against a washer 47 having a concave upper side to fit against the under side of the diaphragm 36 and clamp the same against a clamping plate 48 fitted against the upper side of the diaphragm and abutting the shoulder 45. Obviously, when the nut 46 is turned home, the diaphragm will be securely clamped against the plate 48 and the said plate will be clamped against the shoulder 45 of the plunger so that the diaphragm will be caused to flex and rise and fall as the plunger rod is reciprocated. It will be noted that the plate 48 has an appreciable area and that its under side is convex so that the diaphragm will be supported over an appreciable portion of its extent and, consequently will not bend sharply when

flexed and will be, therefore, protected against undue wear which would induce cracking and breakage.

Upon the upper side of the cover 38 is provided a post or standard 49 having an offset 50 at its upper end disposed in the vertical plane of the operating lever 42 and in the said offset is mounted a stop screw 51 which is adjustable toward and from the lever so as to project more or less into the path of the same and thereby regulate the stroke thereof. Usually the bowl will be provided with such capacity as will measure the quantity in which the liquid is generally dispensed. It may, however, be at times desired to sell a less quantity, and when this occasion arises the stop screw 51 will be turned so as to ride downwardly through the offset 50 and consequently shorten the stroke of the operating lever. It may be found also that through wear incident to long-continued use, or to differences in the consistency or other qualities of various liquids some adjustment of the lever stroke may be needed after the apparatus has been set up for use and this adjustment may be easily accomplished by manipulation of the stop screw.

A counter 52 is provided on the cover 38 to register the number of sales made, and this counter may be of any well-known form, the details thereof forming no part of my present invention. The counter is operated by a rocking arm 53 secured to and extending from the counter shaft of the tally mechanism and connected with the operating lever by a link 54 having one end pivoted to the said rocking arm and its opposite end pivoted upon a stud 55 extending laterally from the lever, as shown.

Liquid commodities, as is well known, vary in characteristics, some being comparatively free of solid constituents while others contain a large proportion of solid elements. Moreover, the solid matters vary in their qualities and in weight so that some times the solid matters in the commodity settle quickly to the bottom of the container. It is obviously desirable to counteract this settling of the solid elements of the commodity and distribute such elements evenly through the liquid volume so that the portion of the commodity withdrawn by the action of the pump will be uniform in quality and composition. To this end, I provide an agitator consisting of a central hub or sleeve member 56 slidably mounted upon the pump tube 6 and adapted to rest by gravity upon the upper edge of the annular enlargement 7. Radiating from the sleeve or hub 56 are agitator arms 57 and attached to two opposite arms are operating rods 58 which extend upwardly therefrom through the cover 38 at opposite sides of the bowl and are equipped at their upper

ends with loops 59 constituting handles. Before operating the pump to withdraw a portion of the liquid contents of the container, the loops or handle members 59 are grasped and the agitator then rapidly reciprocated vertically for a few strokes so that the arms 57 will be caused to work through the liquid and effect such an agitation and circulation of the solid elements as will effectually distribute them through the body of the liquid so that, when the pump is subsequently operated, the portion of the liquid withdrawn will be up to standard in its composition.

Assuming the apparatus to be at rest and the container supplied with the liquid commodity, the several parts will assume the positions shown in Fig. 1. Some of the liquid will rise within the pump tubes 6 and 8 to the level of the liquid in the container but the check valves 16 and 32 will be seated immediately upon the liquid reaching the same level in the container and in the pump tubes. If the lever 42 be now raised, the diaphragm will be flexed upwardly and suction will be created above the valve 32 to unseat the same, whereupon liquid will flow past said valve to fill the bowl below the diaphragm and up to the diaphragm, the liquid being held in the bowl by the check valve 25. When the lever has been raised to the limit permitted by the stop screw 51, the bowl will be filled and the lever is then swung downwardly so as to exert pressure through the plunger rod and the diaphragm upon the liquid, seating the valve 32 and unseating the valve 25 so that the liquid will then flow through the discharge nozzle 20. The gate 21 will be manually raised, of course, so that the outflowing liquid may pass at once into the receptacle provided for that purpose.

All of the liquid below the diaphragm will, of course, pass out through the discharge nozzle 20, except that minute portion which may be trapped in the channel 23 and this portion will constitute a seal below the check valve 25 to prevent possible leakage of air through the nozzle past said valve into the bowl to detract from the accuracy of the apparatus in measuring the quantity withdrawn.

It will be noted that I have provided a measuring pump of very simple and compact construction which may be produced at a low cost and may be readily applied to any container. In applying the pump to a container, it is necessary merely to provide an opening in the top of the container of the proper diameter to snugly receive the closure head 2 and adjust the pump tubes 6 and 8 so that the combined effective length thereof will be approximately the same as the height of the container whereby the inlet head 11 will rest upon the bottom of the

container. The device is exceedingly simple in operation so that it may be manipulated by unskilled or careless persons without detracting from its accuracy as its operation merely requires that the handle lever 42 be raised until the movement is checked by the stop 51 and then pressed downward until it comes to rest which will be effected by the fork 41 at the upper end of the plunger rod coming in contact with the upper extremity of the central guide 39. The guide box or plug 27 is threaded into the upper side of the discharge spout 20 and the opening which receives it is of such diameter that the valve 25 may be withdrawn therethrough when assembling the parts or when repairing or renewal of the same is necessary. To obtain access to the interior of the bowl for cleaning or repairing the parts, it is only necessary to remove the bolts securing the cover upon the bowl, and, likewise, the hub member 29 is threaded into the closure head 2 so that the entire bowl as an entirety may be removed therefrom. The diameter of this hub 29 is such that access may be had through the bottom thereof to the stop washer 34 to permit the assembly or disassembling of the valve 32 and the employment of the intermediate coupling collar 12 facilitates the assembling or disassembling of the valve 16 with the head 11.

Having thus described the invention, I claim:

1. A measuring pump comprising a bowl having a depending integral hub member on the under side of its bottom, a laterally extending discharge nozzle at the side of the hub member and opening through the bottom of the bowl, said nozzle being integral with the bowl and the hub member, a closure to be fitted in a container for liquid and having a depressed portion into which the said hub member is removably fitted, means carried by said closure to establish communication between the lower portion of the container and the bowl through the hub member, a check valve mounted in the upper end of said hub member and controlling the flow into the bowl, an opposed check valve in the nozzle controlling the flow therethrough, and means within the bowl for drawing liquid thereinto and discharging liquid therefrom.

2. A measuring pump comprising a closure head to be secured in a container for liquid, a bowl secured on said head and communicating through the head with the container, means for drawing liquid into the bowl and discharging it therefrom, a tube secured in and depending from said closure head, a second tube fitting telescopically within the first tube, an open-ended inlet head detachably secured upon the lower end of the second tube and constructed at its lower end to rest upon the bottom of the con-

tainer and permit flow of liquid into the head, a valve seat within said head, a guide in the head below the valve seat, a valve adapted to rest on the seat and having a stem 5 depending therefrom through the valve seat and the guide, and a stop washer secured on the stem below the guide.

3. A measuring pump comprising a bowl having a hub member depending from its 10 bottom and constituting an inlet, a valve controlling flow through the hub member, a discharge spout extending laterally from the bowl, a sealing channel below the bowl opening at one end through the bottom of the 15 bowl and at its other end through the bot-

tom of the discharge spout whereby to establish communication between the bowl and the discharge spout, the spout having an opening in its top immediately over the end of the channel, a valve insertable through the 20 opening in the top of the spout to seat in the end of the channel, a stem rising from said valve, a plug closing the opening in the top of the spout and forming a guide for the valve stem, and means within the bowl for 25 drawing liquid thereinto and discharging it therefrom.

In testimony whereof I affix my signature.

OLIVER J. MOUSSETTE. [L. s.]
